UNITED STATES PATENT OFFICE.

EDGAR W. HAZAZER, OF NEW YORK, N. Y., ASSIGNOR TO HAZAZER & STANLEY, OF SAME PLACE.

ELECTRIC BELL.

SPECIFICATION forming part of Letters Patent No. 362,005, dated April 26, 1887.

Application filed December 16, 1886. Serial No. 211,760. (No model.)

To all whom it may concern:

Be it known that I, EDGAR W. HAZAZER, of New York city, in the county and State of New York, have invented a certain new and useful Improvement in Electric Bells, of which the following is a specification.

The object of my invention is to produce a simple, cheap, and efficient electric bell, and especially to provide a simple and efficient means for attaching the bell to the wall or other support, and making the connections between the electrical portions of the bell mechanism and the wires extending to it, whereby the binding - posts, which have heretofore been placed upon the bell-case, and which are expensive and unsightly, are done away with.

To this end my invention mainly consists in providing a suitable back or base plate for supporting the bell, on which are placed suitable contact plates or devices, and in providing the bell-case or bell mechanism with corresponding contact devices, whereby when the case holding the mechanism is secured upon such back or base plate the electrical connections are at once completed through the bell mechanism, the wires having been already connected with the base-contacts; and my invention further consists in the various novel devices and combinations of devices employed by me in accomplishing the above-named objects, as hereinafter set forth and claimed.

My invention is illustrated in the accompanying drawings, in which—

Figure 1 is a rear elevation of the case inclosing and supporting the bell mechanism; Fig. 2, a vertical section on the line xx of Fig. 1 of the bell and base-plate; Fig. 3, a front elevation of the base-plate, and Fig. 4 a vertical section thereof.

A is a suitable base-plate, of wood or other insulating material, having screw-holes $a a$, whereby it may be secured by screws b to the wall B, or other suitable object. The plate A is provided with two small binding-screws, c and c' , and has also inserted in it from the back, before placing it upon the wall, an externally and internally screw-threaded thimble, d . The insulated wires $e e'$ of the bell-circuit, extending through or along the wall B, pass through plate A, and are connected, respectively, to binding-screws c and c' , and from

binding-screw c' a wire, e^2 , extends through the wood of the base and is secured beneath the head of the thimble d . From binding-screw c a flat contact spring, f , extends. It is evident that the contacts might be placed directly upon the wall instead of upon a base-plate, though the use of such base-plate is obviously preferable.

C is the box inclosing and carrying the works of the bell. It is preferably cast in one piece of iron and with a projecting arm, D, extending above it, carrying the gong E, and with an aperture, g , through which the bell-arm F passes. The box C is adapted to fit over and be secured upon the base-plate A.

G are the magnet-spoils, whose cores are preferably secured directly to the iron box, which therefore forms the yoke or back piece of the magnet. Upon the insulating-head h of one of the spools is set a small metal pin, i , to which one end of the magnet-wire i' is attached.

H is the vibrating armature, carrying the bell-arm F. This armature consists of an iron strip having a slot at its pivoted end, forming tongues $l l$, which are bent out in opposite directions and formed into bearing-pins $m m$, one of which is stepped in a socket, n , formed in the front of the box, while the other enters an aperture in a plate, o , secured to a shoulder or a lug, p , formed in the corner of the box. The armature carries a circuit making and breaking spring, r , which makes and breaks contact with the adjustable contact-screws, extending through the side of the box, and preferably arranged and constructed as set forth in my patent reissued October 21, 1884, No. 10,533. The magnet-wire i' extends to screw s . Another spring, t , extends from the other end of the armature and rests against a screw, u , preferably a split screw, which is adjustable through the case, whereby the tension of spring t and the movement of the armature may be adjusted.

It will be seen that the circuit through the bell mechanism is as follows: From pin i around the magnets by wire i' and to screw s , thence to the armature, and thence by the armature-bearings and spring t to the case.

In placing the bell in position the plate A is first secured to the wall and the circuit-connections made thereto, as already described,

and the box C is then placed over the plate, and is secured thereto by the insertion of the long screw *v*, which passes through the front of the box, a sleeve or bushing, *w*, being preferably provided to make a guide and a good bearing for the screw, and into the thimble *d*. This furnishes a secure mechanical connection between the box and the back plate, and at the same time completes the electrical circuit by joining the box with thimble *d*, the circuit being then: wire *e'* to binding-screw *c'*, contact-spring *f* to pin *i*, through the bell mechanism to the box, as already explained, by screw *v* to thimble *d*, wire *e''* to binding-screw *c* and circuit-wire *e*.

It will be seen that an exceedingly ready and simple arrangement for placing the box in position and making the connections is thus provided. None of the wires and none of the electrical connections are exposed, and the expensive binding-screws which it has heretofore been necessary to place upon the outside of the box are dispensed with.

What I claim is—

- 25 1. The combination of a base-plate, circuit-wires extending thereto, and terminals for said wires upon said base-plate, a box inclosing and carrying the works of an electric bell, means for securing said box upon said base-plate, and means for completing circuit from the base terminals through the bell mechanism, substantially as set forth.
- 30 2. The combination, with a base-plate provided with contacts, of a box inclosing and carrying the works of an electric bell and corresponding contacts carried by said box, whereby the bell-circuit is completed by the attachment of the box to the base-plate, substantially as set forth.
- 35 3. The combination of an insulating base-plate provided with contacts, a metal box inclosing and carrying the works of an electric

bell and forming part of the bell-circuit, an insulated contact carried by said box adapted to meet one of said base-plate contacts, and a securing device electrically and mechanically connecting said box with the other base-plate contact, substantially as set forth.

45

4. The combination of the insulating base-plate, the thimble secured therein, to which a circuit-wire is connected, the metal box inclosing and carrying the works of an electric bell, the screw passing through said box and entering said thimble, and electrical connections, whereby the bell-circuit is completed by the insertion of said screw, substantially as set forth.

5. The combination of the insulating base-plate, the contact-spring thereon, the metal inclosing-box, the pin on the magnet-head adapted to meet said spring, a circuit from said pin through the bell mechanism to the box, and a securing device for said box, whereby the circuit is completed by the attachment of said box to said base-plate, substantially as set forth.

6. The combination of the insulating base-plate, the metal thimble secured therein, to which a circuit-wire is connected, the contact-spring secured to said plate and to which the other circuit-wire is connected, the metal inclosing-box, the pin on the magnet-head adapted to meet said contact-spring, connections through the bell mechanism from said pin to the box, and the screw passing through said box and entering said thimble, substantially as set forth.

This specification signed and witnessed this 9th day of December, 1886.

EDGAR W. HAZAZER.
